(57) **CLAIM**

The ornamental design for a wearable fishing rod holder, as shown and described.

DESCRIPTION

FIG. 1 shows a perspective view of a wearable fishing rod holder;

FIG. 2 shows a front view of the wearable fishing rod holder;

FIG. 3 shows a rear view of the wearable fishing rod holder;

FIG. 4 shows a right side view of the wearable fishing rod holder;

FIG. 5 shows a left side view of the wearable fishing rod holder;

FIG. 6 shows a top plan view of the wearable fishing rod holder; and,

FIG. 7 shows a bottom plan view of the wearable fishing rod holder.

The shade lines in the Figures show contour and not surface ornamentation.

The broken lines shown in the Figures show portions of the wearable fishing rod holder device which form no part of the claimed design.
